Charles H. Cady, INVENTOR,

Willard Eddy, BY ⁰ ATTORNEY.

UNITED STATES PATENT OFFICE.

CHARLES H. CADY, OF OMAHA, NEBRASKA.

PHOTOGRAPHIC MASK.

1,399,189.

Specification of Letters Patent.

Patented Dec. 6, 1921.

Application filed October 19, 1920. Serial No. 418,062.

To all whom it may concern:

Be it known that I, CHARLES H. CADY, a citizen of the United States, residing in the city of Omaha, county of Douglas, and 5 State of Nebraska, have invented certain new and useful Improvements in a Photographic Mask, and have described the same in the following specification, illustrated by the accompanying drawings.

10 My invention relates to that class of masks which are commonly used in the process of photographic printing for the purpose of intercepting the actinic rays between the marginal portions of the negative plate and the corresponding portions of a piece 15 of sensitized paper applied thereto, and which individually comprise a sheet of opaque material having an opening where the printing rays pass through. It is the 20 main object of my improvements to adapt a mask of this class to be used with speed and efficiency in the printing of combination photographs, so called, comprising individually a plurality of single photographs 25 printed successively on a single sheet; to expedite the operation of printing such combination photographs; and to facilitate the due alinement and uniform spacing of the single photographs printed on the single 30 sheet. To accomplish these results, I incorporate in my improved photographic mask, as parts thereof, a backing sheet which has a longitudinal guideway and an exposure opening, and a mask proper which is 35 slidable in the guideway and has a plurality of windows adapted to register with the exposure opening successively.

In said drawings, illustrating the best manner in which I have contemplated applying the principles of the invention, Figure 40 1 is a perspective view of the backing sheet of a mask which is constructed in accordance with these principles. Fig. 2 is a like view of the mask proper of the same photographic mask. Fig. 3 is a like view of the same entire mask and an applied strip of sensitized paper, all operatively assembled. Fig. 4 is an enlarged cross section on the section line of Fig. 1, and shows 45 50 the backing sheet, the mask proper, the sensitized paper and a photographic negative plate, all operatively assembled.

In this illustrative specimen of my invention, the backing sheet is denoted by the 55 numeral 6. This is a flat strip of thick dark paper, or other material impervious to

actinic rays, and has a central exposure opening 7, which is of proper size and shape to fit the negative plate 8 and to permit the latter to be adjusted therein by a slight 60 movement of translation transversely of the strip. It has opposite upturned edge portions 9, mutually parallel and folded over toward each other to serve as retaining guides for the mask proper which is to be 65 inserted in the guideway between them. Likewise it has a pair of terminal wings, or flaps 10, which are joined to the body of the sheet by the folds or hinges 11 and are adapted to overlap one another when folded 70 together.

The mask proper is also a flat strip of similarly impervious material, 12. It has a plurality of alined exposure openings, or windows, 13, which are slightly smaller than 75 the exposure opening 7, are uniformly spaced apart, and are severally adapted to register centrally with that opening. It is slightly shorter than the body of the backing sheet 6, in order that it may be confined 80 thereto by the closing of the wings 7, when the apparatus is not in use. It is of suitable width to be slidingly adjustable endwise under and between the retaining guides 9; is inscribed with visible characters, such as 85 the numerals 1 to 5 inclusive, to identify the several windows 13 and to distinguish them from each other; and is provided with the marginal stop guides 14, which are strips of paper stuck to the face of the mask proper 90 to aid in adjusting and retaining in position thereon a strip of sensitized paper 15 over the windows 13, as shown in Fig. 3. These guides locate or define the seat of the sensitized paper on the mask in the position 95 shown in Fig. 3.

In the use of this mask, the photographer first lays the backing sheet flat on the glass top of a printing machine of any ordinary type, not shown in the drawings, and inserts the selected negative plate 8 in the exposure opening 7, as shown in Fig. 4. As need may require he adjusts this negative 100 therein transversely of the strip. Then, by inserting the mask proper under and between the guides 9, and by sliding the same endwise in the guideway formed by them, he covers therewith the marginal portions 105 of the underlying negative plate, and the edges of the opening 7 wherein it is contained, as well as all the lines or spaces of separation between the plate and these edges, 110

and exposes the central portion, or sight, of the negative at any one of the windows he may have selected for the purpose, as, for example, the window 1. Then he lays and 5 adjusts the strip of sensitized paper flat on the face of the mask proper in contact with the stop guides 14, as shown, and causes the same to remain in that position while the printing from the selected negative takes place in the usual manner. Then 10 with another negative, substituted for the first, and with the mask proper and the sensitized paper thereon similarly adjusted to a substituted position, as, for example, 15 with the window 2 over the sight of the negative, he repeats the same operation; and continues repeating the operation with other negatives until the several constituent single photographs of the resulting combination photograph have been successively 20 printed on the single strip of sensitized paper through the several windows 13 respectively.

I claim as my invention—

25 1. A photographic mask comprising a backing sheet having a longitudinal guide-

way and an exposure opening, which is adapted to accommodate in succession a plurality of negative plates adjustable in the opening, a mask proper adapted to slide 30 in the guideway and having a plurality of aligned windows adapted to register successively with the exposure opening, and a seat for sensitized paper on the face of the mask proper.

2. A photographic mask comprising a backing sheet having an exposure opening for the accommodation of a succession of negative plates adjustable therein, a mask proper having a plurality of windows and 40 slidable in a guideway on the backing sheet so as to uncover at the windows in succession a middle portion of the exposure opening and of a negative plate therein, while covering marginal portions of the same, and 45 means for seating a piece of sensitized paper on the face and over the windows of the mask proper.

Witness my signature at Omaha, Nebraska, October 16, 1920.

CHARLES H. CADY.
